PACKAGE

Maxwell Knorpp, Long Island City, N. Y., assignor to Knorpp Candy Company, Brooklyn, N. Y., a Corporation of New York

Application October 30, 1931. Serial No. 572,021

2 Claims. (Cl. 206—44)

The present invention relates broadly to packaging and more especially to a display package for frangible food products.

The present invention comprises more particularly a container for a plurality of edible objects such as marshmallow chicks, rabbits, or the like, which are sold primarily due to appearance and shape of the molding, and, therefore, the element of display is a major factor 10 in the sales thereof.

Another feature is that while the objects are displayed for view, they are of such nature as require protection from dust and dirt and also require sealing to retain normal moisture, and 15 because of the price at which such objects must be sold, the cost of the package must necessarily be low.

The present invention provides a solution for the above problems by comprising a plurality 20 of open compartments wrapped in a sealed film of the type known to the trade as "cellophane". More especially, the preferred form of the invention comprises an open frame in which a partition unit member is set with the merchandise arranged in cells provided by the partition unit and with the frame and partition unit 25 completely covered with transparent cellophane or the like so that both sides of the package are open for clear vision to permit the purchaser to have a complete view of the goods, while the goods are thoroughly protected from dust and dirt and the normal moisture and aroma of the goods are sealed in the package.

Another feature of the present invention is 35 that the frame which may carry advertising and ornamentation is preferably collapsible and the partition unit adapted to be mounted in the frame is likewise collapsible so that the package materials may be stored in a relatively small 40 space. When the frame is expanded and the partition unit set in place therein and the goods placed in the compartments or cells and the whole sealed in cellophane, the cellophane covering resists forces tending to distort the package 45 age so that the complete package becomes a sufficiently rigid unit capable of withstanding shipping and handling stresses without danger of collapse.

Other and further objects of the present invention will in part be obvious and will in part 50 be pointed out hereinafter by reference to the accompanying drawing forming a part of the disclosure herewith. It is to be understood that the disclosure is illustrative and not to be considered in the limiting sense.

Fig. 1 is a perspective view illustrating the completely formed package.

Fig. 2 illustrates the elements of the package partially disassembled.

Fig. 3 is a cross section on line 3—3 of Fig. 1. 60 The preferred form of the package comprises a cardboard open frame member which, when expanded, comprises a rectangular frame A having top and bottom members 1 and side members 2. A partition unit B is adapted to set into said 65 frame A and preferably, the partition unit comprises strips of cardboard forming shelves 4 and other strips of cardboard comprising partitions 5. The strips of cardboard are each slotted one half of their width in order that the shelf members 70 may be telescoped over the partition members until the edges of both members lie substantially in a common plane. When the shelf members 4 and the partition members 5 are interlocked and set in expanded relation, cells or 75 compartments 6 are formed to hold merchandise 8. The merchandise 7, in the present case illustrated as marshmallow chicks, are placed in the compartments and a film of cellophane C is wrapped around the entire package in such manner as to provide two transparent sheets, one on 80 each side of the package to comprise windows 8 through which the goods may be viewed for either side of the package, while at the same time thoroughly sealing the goods against contamination and retaining the moisture in the package. The ends 9 of the shelves 4 and the ends 10 of the partitions 5 contact with the frame and provide spaces 11 and 12 around the merchandise cells so that the goods are protected from extraneous shocks delivered to the frame A during shipping and handling.

The frames and the partition members are so constructed as to fold flat when stored and to be expanded when ready for receiving the merchandise. The cellophane wrapper around the package sustains any stresses tending to distort the assembled units so that a substantially rigid package is provided for shipping, handling, and display.

The top, bottom, and sides of the frame A are adapted to receive ornamentation and titles so as to provide an ornamental package in which display merchandise is offered to the public in an attractive manner.

What I claim is:

1. A display package comprising a frame open on two opposite sides, a partition member comprising a plurality of compartments open on correspondingly opposite sides, means carried by 110

- said partition member for spacing the compartments adjacent said frame from said frame to provide shock absorbing spaces between the frame and the compartments, and a transparent 5 wrapper forming a complete covering for said package whereby merchandise in said compartments is substantially completely visible.
2. A display package for merchandise comprising a frame of strip material open on two opposite sides, a filler comprising interlaced strips 10 adapted to be interlocked to form a plurality of compartments open on correspondingly opposite sides, the ends of said strips of said filler extending beyond said compartments and into engagement with the inner side wall of said frame to form spaces between said compartments and said frame, and a sealed transparent wrapper forming a complete covering for said package whereby said goods may be viewed without breaking said wrapper. 80
